UNITED STATES PATENT OFFICE.

DARIUS MUSSelman, OF CHARITON, IOWA.

COMBINED STEAM AND HOT-AIR ENGINE.

Specification of Letters Patent No. 32,200, dated April 30, 1861.

To all whom it may concern:

Be it known that I, DARIUS MUSSelman, of Chariton, in the county of Lucas and State of Iowa, have discovered a new and useful 5 Mode of Generating and Combining Hot Air, Steam, and the Gaseous Products of Burning Fuel as a Motive Power for Propelling Machinery; and I do hereby declare that the following is a full, clear, and exact 10 description of the construction of the same, reference being had to the annexed drawings, making a part of this specification.

In the drawing Figure 1, A, is the furnace chamber, which with furnace B, and other 15 parts interior to chamber A, is shown by dotted lines. Chamber C, shown by full lines, is a strong airtight chamber completely surrounding chamber A, with a cold air space between them, for the passage of 20 the cold air from the air pump D, to the furnace B. The arrows in the air space show the direction of the air in its course from air pump D, to furnace B. The pipe E, conducts the heated air and gases from the furnace 25 to the space F, beneath and surrounding the lower part of the steam generator G, which last is extended through chambers C, and A', its lower part being contained in the latter chamber. H, is a pipe within the 30 steam generator, through which the hot air and gases pass from space F, into the steam generator g.

K, is a stack of circular perforated plates, fitted to the interior of the steam generator, 35 and arranged in a frame about a half an inch apart.

L, is a pipe pierced with a great number of small holes, located inside of generator G, and extending to the bottom of the latter in 40 contact with its side, through which pipe the water from the force pump enters the generator, sprinkling the adjacent plates and the lower part of said generator.

M, is a pipe connecting the steam generator 45 to the engine.

N, is a plunger tapered at its lower extremity, working air tight in the short tube O, by means of metallic packing fixed in said tube. The upper end of plunger N, is 50 attached to lever a, which is made adjustable by means of notched post b, against which said lever is pressed by spring rod c', the other end of lever a, is attached to spring d, a pointer is fixed to the latter to indicate

on scale e, the pressure in pounds to the 55 square inch on plunger N. The scale post e, with the rod f, serves also as a support to lever a, and plunger N. The arm g, attached to the plunger N, rises and falls with the latter, giving motion to rod h, which 60 passes through stuffing box k, and is attached to sliding valve l, which last is inserted in pipe P, which extends down into space F. The aperture m, in pipe P, opens 65 into the cold air space between chambers A, and C. The aperture n, opens into the hot air space F.

The design of plunger N, and the devices connected with it, is to prevent the production of a greater amount of motive power 70 than is required to propel the engine at the proper force and speed. Thus, when the hot air entering the generator tends to produce more than the required amount of motive power; the increased pressure acting on 75 plunger N, causes the latter to rise, by which valve l, is raised so as to partly close aperture m, and at the same time leave n, partly open; which shuts off a portion of the air flowing from the air pump to the fire, and 80 turns it into space F, where it mixes with the overheated air entering the steam generator from the furnace, which mixing, instantly checks the tendency to produce surplus power. When a high pressure is desired, lever a, is brought down to one of the 85 lower notches in post b, which at the same time lowers plunger N, and sliding valve l, so as to require a great increase of pressure to raise valve l, sufficiently high to turn a 90 portion of cold air into hot air space F. For a low pressure, lever a, is placed in one of the upper notches in post b. In case of a great and sudden expansion of steam &c. in the generator, plunger N, will rise sufficiently high to allow the surplus power to escape,—the taper of the plunger, at its lower extremity, when opposite the packing ring, allowing said escape, without said plunger rising entirely above the packing 95 ring. This device, in connection with those for modifying the heat of the air in space F, will effectually prevent explosions.

The float o, in the steam generator, (Fig. 2,) attached to rod p, actuates valve q, in 100 tube r, through which last the water flows to the force pump, preparatory to its admission into the steam generator. When the

water in the generator is at the proper height, the valve *q*, shuts off a portion of water from the pump equal to the excess of that required in the generator. The float *o*, 5 is pointed at its lower extremity giving this part the form of an inverted cone to prevent undue buoyancy by the boiling or agitation of the water in the steam generator. The water in the steam generator may cover the lower end of pipe *H*, so that the hot air passing through the latter into the generator, throws the water upward in the form of spray.

The fuel feeder *q*, contains two valves *s*, 15 and *t*, formed of plates of metal arched to give greater strength. Each valve has a small opening near the points where they are hinged, which are closed airtight by rods *u*, and *v*, which slide beneath valves *s* and *t*. 20 The valve *t*, has attached to its upper side a protecting plate, to prevent injury to said valve when feeding fuel to the furnace. The door *w*, beneath valve *t*, opens into the furnace. Lever *x*, actuates the rods *u*, and *v*, 25 for opening and closing valves *s*, and *t*. In feeding fuel to the furnace, lever *x*, is moved so as to withdraw rod *u*, from beneath valve *s*, when the escape of condensed air that may be between the valves *s*, and *t*, through the 30 opening in valve *s*, allows the latter to fall. Fuel is then placed in the fuel feeder, resting on the protecting plate attached to valve *t*, lever *x*, is then moved so as to push rod *u*, against valve *s*, raising the latter to its place. 35 By pushing rod *u*, somewhat farther beneath valve *s*', valve *t*, is allowed to fall, by the withdrawal of rod *v*, from beneath the latter valve,—dropping the fuel upon door *w*, which opens by the weight of said fuel, 40 which falls thence into the furnace. Door *w*, rises to its place by means of weights or springs attached to it for that purpose. Door *w*, may be composed of two shutters. Lever *x*, keeps both valves closed, but will 45 not allow but one to be open at the same time. As a general rule, both valves should be kept closed during the intervals of supplying fuel to the furnace.

It is evident that some means must be 50 provided to prevent soot and ashes from being carried into the hot air space *F*, and thence into the steam generator *G*. This is accomplished by the peculiar form and arrangement of pipe *E*, which conducts the 55 hot air from the furnace *B*, to the hot air space *F*. The side of pipe *E*, next the furnace, and the bottom of said pipe next the ash pan, *R*, has a slit or seam in its whole length communicating with ash pan *R*. A 60 device similar to the twist of an auger is fitted into pipe *E*, extending the whole length of the latter. The furnace *B*, and ash pan *R*, are separated from the hot air space *F*, by a partition *S*, crossing furnace

chamber *A*, vertically between the furnace 65 *B*, and hot air space *F*, and horizontally between the latter and ash pan *R*. Partition *S* rests against that side of pipe *E*, next the furnace, and the lower part of said pipe next the ash pan *R*. Both the vertical and horizontal 70 parts of this partition, have a slit or seam coinciding with that in pipe *E*. Thus, the hot air from the furnace, in passing toward space *F*, acquires while passing through pipe *E*, a whirling motion, by 75 means of the twisting form of the device contained in said pipe. This whirling motion causes the soot and ashes that may be borne along with the hot air, to tend outward from the center of pipe *E*, by which it 80 is thrown through the seam or slit in said pipe, falling thence into ash pan *R*. A portion of the hot air also passes through the seam in pipe *E*, with the soot and ashes, and reenters the furnace through the grate beneath the fire, by which it is reheated and passes into pipe *E*, as before. This return 85 of a portion of the hot air to the furnace, being continual, gives a higher temperature to the whole body of hot air passing into 90 space *F*, and generator *G*. Fig. 3, gives an end view of pipe *E*, showing its connection with partition *S*.

The combined operation of all the parts embodied in the preceding descriptions, remains to be described. The engine, to which my invention is applied, should have a cylinder of three or four times the capacity of the air pump *D'*, or two thirds that of the steam generator *G*. The air pump *D*, is 100 worked stroke for stroke with the engine. Preparatory to starting the engine, the force pump and air pump are disconnected from the engine gearing. Air pump *D*, is then worked by a lever, which forces condensed air into chamber *C*, which with its interior parts, including generator *G*, now forms a reservoir of condensed air for starting the engine. The force pump is then worked by hand, by which a small quantity 105 of water is forced into the generator, sprinkling the plates *K*, and covering the bottom of the generator a few inches deep. The pumps are now connected with the engine as before. Fuel, well ignited, is now placed in 110 the fuel feeder filling two thirds of the space between the valves, which is dropped into the furnace in the manner already described. The valve admitting the motive power to the engine is now opened. The introduction 115 of the burning fuel into the furnace, by heating and expanding the air therein and augmenting its pressure, sets the engine in motion. One or two revolutions of the machinery causes the highly heated air from 120 the furnace to enter the generator, which almost instantly causes an evolution of steam, by heating the water contained there-

in. All the plates opposite the sprinkling pipe L, are covered by water. The under surfaces of the plates are also sprinkled with water, by the upward force of the hot air 5 and steam flowing to the engine. The plates above pipe L, are intended to prevent water from being carried to the top of the generator, and while arresting it, forming also additional evaporating surface. Thus, nearly 10 all the plates serve as evaporating surfaces, exposing the water to the direct contact of the highly heated air from the furnace, which direct contact will convert water into steam at least six times as rapidly, as can 15 be effected, with an equal heating surface, in an ordinary steam boiler, forming altogether an immense steam producing capacity in a very small space. A very small amount of fuel will maintain the power of 20 the engine.

The method described, for putting the engine in motion will serve for small and moderate sized engines. Large engines will require a small hand pump to supply chamber C, with condensed air preparatory to setting the engine in motion. A reservoir communicating with pipe P, may also be an advantage to large engines, on which the hand pump in the last case should be located, so that said reservoir may be supplied with condensed air, with either the engine, or hand pump. When the engine is not in motion, the fuel ceases to burn except in a small degree. For engines that are often 30 required to stop, there will be required a small engine and air pump, (termed a doctor,) to supply the fire with air sufficient to maintain a slow combustion while the larger engine is at rest.

40 The ash pan R, and furnace B, are removable; the head of chamber C, being taken off for that purpose; which should be done once a day to remove the ashes accumulated in them.

45 The constant agitation of the water in the generator prevents mud, lime, and other impurities from adhering to its interior, by being kept in solution in the water, which latter should be expelled once a day through 50 mud pipe T, and its place supplied by fresh water. When the engine stops for any considerable length of time in cold weather, the water should be expelled, which being small in quantity may be supplied fresh in 55 one or two minutes, thus obviating the difficulties incident to freezing.

60 The escape steam, &c., from the engine may be employed to heat the water previous to its admission into the generator, which will effect a saving of fuel. Much less water is required, than in common steam engines.

In starting large engines, the head of chamber C, may be opened and fire kindled

in the furnace while partly drawn out; but 65 the condensed air from the reservoir must be admitted to the fire immediately on closing the head of chamber C; otherwise the want of air will extinguish the newly kindled fire.

Sometimes the pressure in the steam generator, may be for a moment, greater than 70 in the furnace; and when this is the case, the valve on the end of pipe H, prevents the water from being forced out of the generator 75 into space F.

It may be observed, that no part of my apparatus, subject to pressure, is liable to be overheated. The condensed air from the 80 air pump, previous to entering the furnace, circulates on all sides of the latter, in the air space between the furnace chamber A, and the outer chamber C, by which the latter is kept cool. The hot air from the furnace, after entering the generator, loses 85 a large portion of its heat by mixing with the water, by which said generator is prevented from being overheated.

With good material used in the construction of my invention, there can be no danger of an explosion. The metal used should be capable of sustaining a pressure considerably above that assigned as the highest limit of pressure used in running the engine. When explosions occur from neglect 95 of this precaution, there can be but little damage as the result, in consequence of the small space occupied by the motive power.

Any kind of engine may be used with my invention, that can be used with steam or 100 hot air separately. The weight and size of my invention need not be more than one fifteenth the size of steam boilers, (with their adjuncts,) commonly in use, of the same power.

The supply of air to the furnace, and the admission of the water to the generator, being regulated by automatic devices, render the working of my invention free from nearly all difficulties caused by negligent 110 attendants. The small amount of fuel consumed, renders it necessary for but one man to supply fuel to the furnace, even for large engines.

I do not claim the precise form and arrangement of the parts composing my invention; as said form and arrangement may be varied, and yet retain the essential principles embodied in them. Nor do I claim the form and arrangement of the air pump, 120 which latter is well known.

I claim—

1. The arrangement of the devices as set forth by which soot or ashes is prevented from entering the generator; which devices 125 also return a portion of the hot air and gases to the furnace to be reheated.

2. The arrangement of the plunger N,

and the devices connected with it, by which said plunger acts as a safety valve, pressure indicator, and regulator of the air passages for limiting the amount of motive power produced, substantially as set forth.

3. The arrangement of the feeder for introducing fuel into the furnace without per-

mitting the escape of the condensed air contained in the air space surrounding the furnace, substantially as set forth.

DARIUS MUSSELMAN.
